UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

TYPOGRAPHICAL ELEMENTS.

Application filed December 5, 1921. Serial No. 519,861.

To all whom it may concern:

Be it known that I, GEORGE P. KINGSBURY, a citizen of the United States, residing at Brooklyn, in the county of Kings and State of New York, have invented certain new and useful Improvements in Typographical Elements, of which the following is a specification, reference being had therein to the accompanying drawing.

10 This invention relates to slug casting machines, such as linotype machines of the general organization represented in U. S. Letters Patent to O. Mergenthaler No. 436, 532, wherein circulating matrices are released from a magazine in the order in which their characters are to appear in print and then assembled in line, the composed line transferred to the face of a mold, the mold filled with molten metal to form a 15 slug or linotype against the matrices which produce the type characters thereon, and the matrices thereafter returned through a distributing mechanism to the magazine from which they started.

20 In the commercial machines, the matrices are generally provided with roman or italic characters, and in some instances (for the smaller sizes) with both. In the use of characters of either kind, the matrices are 25 presented to the mold in a vertical position and hence the italic characters must be and are inclined with respect to the parallel sides of the matrices. Under such conditions, the italic characters on the cast slugs cannot of 30 course overlap each other, i. e., intersect a line drawn vertically between them, as in the case of perfect italic characters. To avoid the foregoing disadvantage and to permit the casting of slugs with true italic characters, it has been proposed to employ matrices having italic characters arranged 35 parallel to the sides thereof and to present said matrices to the mold in an inclined condition. Such prior proposals are quite satisfactory for the casting of whole or "solid" 40 lines of italics, but it frequently becomes desirable to cast lines which are only partly italicized, e. g., lines made up in part of roman characters and in part of italic characters. Heretofore, this has been done by 45 interposing a triangular-shaped filling piece or spacer between the vertical and inclined matrices, but the use of such a filling piece is not altogether satisfactory, because it involves a considerable separation of the

roman and italic characters and produces too much white space in the printed matter.

The present invention is intended to do away with the foregoing objection and contemplates a construction of the parts where- 60 by the italic characters and the roman characters may be brought into suitable proximity to each other. In carrying out this invention, the matrices bearing the roman characters remain unchanged, which is de- 65 sirable for obvious reasons, but the matrices bearing the italic characters, as well as the spacers or filling pieces, have been modified so as to bring about the desired results. The manner in which these results are accom- 70 plished will best be understood from the detailed description to follow.

In the accompanying drawings, the invention has been shown merely in preferred 75 form and by way of example, and as applied to a linotype machine of the general class stated, but it is obviously susceptible of various other embodiments and adaptations which will still be comprised within its spirit. Thus, for instance, it is applicable 80 to all forms of typographical machines, and this whether such machines employ matrices with intaglio matrices, as herein, or matrices with cameo characters. Generally speaking, it is to be understood that the invention is 85 not limited to any specific form or embodiment except in so far as such limitations are specified in the claims.

Referring to the drawings:

Fig. 1 is a front elevation of a composed 90 line made up in accordance with the present invention and shown in casting condition;

Figs. 2 and 3 are edge and face views, re- 95 spectively, of one of the improved matrices;

Figures 4 and 5 illustrate, in edge and face view, the improved spacers; and

Fig. 6 illustrates a modified or alternative form of matrix.

In Fig. 1, the composed matrix line is shown as made up of five distinct elements, 100 designated A, B, C, D and E, respectively. The elements A are the ordinary linotype matrices, some formed in one edge with intaglio roman characters A⁻¹ arranged thereon for alignment in a vertical position of 105 said matrices, and others being blank or without characters. The elements B are the customary linotype spacebands or justifiers, which are used to expand the line prior to casting between the well known clamping 110

2
jaws or abutments F and G. The elements C are the improved matrices, these being formed in one edge with italic characters C-¹ arranged thereon for alignment in an inclined position of said matrices. The elements D and E are the improved spacers, which preferably, although not necessarily, have no characters formed thereon.

According to the present invention, the 10 matrices C are beveled off on opposite sides and at opposite ends, as at C-² and C-³, respectively, at an angle corresponding to the inclination of the matrices when in casting condition. In other words, each matrix 15 has its two side faces extended parallel to its longitudinal axis from the opposite ends through the character zone and then at an inclination to said axis for the remaining distance. As to the spacers D and E, these 20 are each formed so as to present on one side a vertical face to fit up against a roman matrix A and on the opposite side a partly vertical and partly inclined face to fit up against an italic matrix C. In the embodiment 25 illustrated, the inner face of the spacer D is constituted by two vertical parallel surfaces D-¹ and D-² and an intermediate inclined surface D-³, and the inner face of the spacer E is likewise constituted by 30 two vertical parallel surfaces E-¹ and E-² and an intermediate inclined surface F-³, it being noted, however, that the inclined surfaces D-³ and E-³ are arranged in parallelism with each other and at an angle corresponding to the inclination of the 35 matrices C.

The general effect of the foregoing construction of the parts clearly appears in Fig. 1, where it will be seen that, notwithstanding the different angular positions of the matrices A and C, the space between the adjoining roman and italic characters is reduced to a minimum. This is due, of course, to the beveling off of the matrices C 45 and the corresponding formation of the spacers D and E. In this connection, it is pointed out that the bevel C-³ of each matrix C begins at a point located directly at the character zone, which fact allows the matrix when inclined to be arranged as closely to an adjacent roman matrix as the particular inclination will permit. Thus, taking the last matrix C of the italic 50 group in Fig. 1, the separation of its character C-¹ from the roman character A-¹ of the following matrix A is really due to the thickness of the reduced end of the spacer E, as it is apparent that, if the spacer were omitted, the two characters would come directly together. In the case of the bevel C-², however, the point at which it begins is somewhat above the character zone; hence, taking the first matrix C of the italic group 55 in Fig. 1, by way of example, the separation of the character C-¹ from the preced-

ing roman character A-¹ is slightly greater than that caused by the thickness of the reduced end of the spacer D. The bevel C-² might readily be started from the character zone, if that were desired, but this would be convenient only in connection with the thicker matrices. By starting the bevel at a point above the character zone, as illustrated, it is possible to make use of relatively thin matrices as well as the thicker ones. 70

It will be appreciated that the matrices C, instead of being beveled off in the manner shown and described, might be cut away in some other fashion, if preferred. The main consideration is that the cooperative elements should be so constructed that the plane of the inclined surface of either spacer will cross the perpendicular plane of said spacer on a line located inward of the end of the adjacent inclined matrix. The nearer this line approaches the character zone, the closer the adjacent roman and italic characters may be arranged. It has been seen that, in the case of the spacer E, the line of crossing is located directly at the character zone and that, consequently, the roman and italic characters may be arranged in immediate proximity to each other. In prior constructions, due to the form of the parts, the line of crossing is located at or above the extreme end of the matrix, with the result that there is a very considerable separation of the roman and italic characters. 100

It will also be appreciated that the spacers D and E might be variously modified without impairing their essential functions. To perform these functions, it is simply necessary that each spacer present on its outer side a vertical surface of sufficient extent to contact with a vertical matrix throughout its character zone and on its inner side an inclined surface of sufficient extent to contact with an inclined matrix throughout its 110 character zone. In the form illustrated, the vertical surfaces D-¹ and E-¹ are simply intended to contact with the beveled surfaces C-² and C-³, respectively, while the vertical surfaces D-² and E-² are merely provided to allow the italic matrices C to occupy a vertical position at certain times in their travel through the machine. As a matter of fact, the spacers might be cut off along the line of crossing of their inclined surfaces 115 D-³ and E-³, so as to allow the beveled surfaces of the matrices C to contact directly with the vertical sides of the matrices A, but this would involve special alterations in 120 the regular linotype machine for the handling of the spacers. As now constituted, the spacers are of the same general form or configuration as the matrices and can be handled in the machine in the same way. 125

To permit their circulation through the 130

machine, the matrices A are formed with the customary projecting ears A-² and distributing teeth A-³, the latter being located at the left and the former at the right of the matrices, all in the usual way. The improved matrices C are likewise formed with projecting ears C-⁴, two at the top and two at the bottom. These ears C-⁴, however, are inclined with respect to the longitudinal axis of the matrix, being situated in a plane passing diagonally through the matrix body (see Fig. 2) and located between the beveled surfaces C-² and C-³. This peculiar arrangement of the ears C-⁴ not only provides for the presence of the bevels C-² and C-³ but, in addition, enables the matrices to be circulated through the machine in the usual way. The arrangement is further advantageous in that, when the matrices are tilted to their inclined position, the upper and lower ears approximate a common vertical plane, which is desirable in effecting the alignment of the matrices. As a matter of fact, on the thicker matrices, the inclination of the ears could be made to correspond with that of the matrices, in which event, the upper and lower ears would stand in the same vertical plane in the inclined condition of the matrices. It may be noted that the inner ends of the projecting ears C-⁴ are beveled or inclined, so as to be brought into a horizontal plane when the matrices are tilted to their inclined position (see Fig. 1), and thus to insure the correct alignment of the matrix characters. Needless to say, if the inclination of the ears were made to correspond with that of matrices, as above suggested, no bevelling of the ears would be necessary. The matrices C are also provided at their upper ends with distributing teeth C-⁵, these teeth being located inward of the beveled surface C-² and situated in a plane disposed at an inclination to the longitudinal axis of the matrix so as to extend parallel to the plane of the ears C-⁴.

Fig. 6 illustrates an alternative arrangement of the projecting ears C-⁴ and the distributing teeth C-⁵. In this instance, the ears are situated in a plane located between the bevels C-² and C-³, as before, but this plane in the present form extends parallel to the longitudinal axis of the matrix. Likewise, the distributing teeth C-⁵, although located inward of the bevel C-², as before, are situated in the plane of the projecting ears C-⁴ and hence extend parallel to the longitudinal axis of the matrix.

The spacers D and E are also formed with projecting ears and distributing teeth to permit their circulation through the machine in the same way as the matrices. Thus, the spacer D is formed with projecting ears D-⁴ and distributing teeth D-⁵ situated in the same vertical plane, while the

spacer E is formed with projecting ears E-⁴ arranged at the right and with distributing teeth E-⁵ arranged at the left of the spacer. In each instance, the inner ends of the projecting ears extend at right angles to the perpendicular plane of the spacers so as to locate them in the required vertical position during casting.

It has been deemed unnecessary to illustrate herein the various parts of a linotype machine, as these are well known to those skilled in the art and in themselves form no part of the present invention. For the same reason, it seems unnecessary to discuss the behavior of the elements in the various stages of their travel through the machine. It may be noted, however, that the tilting of the italic matrices takes place during the justification of the composed line prior to casting. That is to say, when the first elevator presents the line between the clamping jaws F and G, the matrices C will at the time be standing in a vertical position, but when the line is subsequently locked up and justified by the closing movement of the clamping jaws and the expansion of the spacebands B, the matrices C are necessarily tilted to their inclined position and the italic characters C-¹ thus brought into proper alignment.

In the illustration given in Fig. 1, there happens to be shown but one group of italic matrices, but it will be apparent that a plurality of groups may be composed in line by the use of a corresponding plurality of pairs of spacers. It is also apparent that the whole line might be composed of italic matrices, if desired.

While the invention is herein illustrated in connection with matrices of the circulating variety, it should be understood that it is equally applicable to matrices of the non-circulating variety, such for example as those presented in the Kennedy U. S. Patent No. 1,193,269, or the Reade U. S. Patent No. 1,207,622. It will be apparent, without additional illustration, that the matrices or matrix sections shown in these two patents could be bevelled off in the manner before described to achieve the results above discussed. In the use of such non-circulating matrices, the spacers could be cut off at the line of crossing of their inclined surfaces, as before suggested, without involving any special alteration of the other parts. It should also be understood that the invention is not confined to single letter matrices, as herein shown, but might be applied to plural letter matrices as well. These and many other adaptations and alterations will readily suggest themselves to those skilled in the art without departing from the spirit of the invention.

The terms "vertical," "perpendicular," "horizontal," etc., are employed herein in a

relative sense only and no limitations are intended.

Having thus described my invention, what I claim is as follows:—

5. 1. In or for a typographical machine, a matrix adapted to occupy an inclined position when in use, the said matrix being cut away on one side and at one end, for the purpose described.
10. 2. In or for a typographical machine, a matrix adapted to occupy an inclined position when in use, the said matrix being cut away on opposite sides and at opposite ends, for the purpose described.
15. 3. In or for a typographical machine, a matrix adapted to occupy an inclined position when in use, the said matrix being beveled off on one side and at one end at an angle corresponding to the inclination 20 of the matrix.
25. 4. In or for a typographical machine, a matrix adapted to occupy an inclined position when in use, the said matrix being beveled off on opposite sides and at opposite ends at an angle corresponding to the inclination of the matrix.
30. 5. In or for a typographical machine, a matrix adapted to occupy an inclined position when in use, the said matrix having 35 its side faces extending parallel to its longitudinal axis from the opposite ends through the character zone and at an inclination to said axis for the remaining distance.
35. 6. In or for a typographical machine, a matrix line or group composed, at least in part, of inclined matrices having parallel sides throughout the character zones, and a vertically disposed spacer having an inclined surface arranged in contact with the 40 side of an adjacent inclined matrix, the said matrix and spacer being relatively formed so that the plane of the inclined surface will intersect the perpendicular plane of the spacer on a line located inward of the end of the matrix.
45. 7. In or for a typographical machine, a matrix line or group composed, at least in part, of inclined matrices having parallel sides throughout the character zones and 50 beveled off on one side and at one end at an angle corresponding to their inclination, and a vertically disposed spacer presenting a partly vertical and partly inclined face to fit up against an adjacent inclined matrix, substantially as and for the purpose set forth.
55. 8. In or for a typographical machine, a matrix line or group composed of matrices having parallel sides throughout the character zones, certain of the matrices occupying 60 a vertical position and others an inclined position, and a spacer interposed be-

tween the adjacent vertical and inclined matrices and presenting on one side a vertical face arranged in contact with the vertical matrix and on the other side an inclined surface arranged in contact with the inclined matrix, the said spacer and inclined matrix being relatively formed so that the plane of the inclined surface will 70 intersect the perpendicular plane of the spacer on a line located inward of the end of the matrix.

9. In or for a typographical machine, a matrix line or group composed of matrices having parallel sides throughout the character zones, certain of the matrices occupying a vertical position and others an inclined position, the latter matrices being beveled off on one side and at one end at an angle corresponding to their inclination, and a spacer interposed between the adjacent vertical and inclined matrices, the said spacer presenting on one side a vertical face to fit up against the vertical matrix and on the other side a partly vertical and partly inclined face to fit up against the inclined beveled matrix, substantially as and for the purpose set forth.

10. In or for a typographical machine, a matrix cut away on opposite sides and at opposite ends and provided with projecting ears at its opposite ends, said ears being situated in a longitudinal plane located between the cut away portions.

11. In or for a typographical machine, a matrix cut away on opposite sides and at opposite ends and provided with projecting ears at its opposite ends, the said ears being situated in a longitudinal plane passing diagonally through the matrix and located between its cut away portions.

12. In or for a typographical machine, a matrix cut away on one side at its upper end and provided at such end with distributing teeth located inward of the cut away portion.

13. In or for a typographical machine, a matrix formed with projecting ears inclined with respect to the longitudinal axis of the matrix.

14. In or for a typographical machine, a matrix formed at its upper and lower ends with projecting ears aligned with each other and inclined with respect to the longitudinal axis of the matrix.

15. In or for a typographical machine, a matrix formed with distributing teeth situated in a plane disposed at an inclination to the longitudinal axis of the matrix.

In testimony whereof, I have affixed my signature hereto.

GEORGE P. KINGSBURY.
